Patented Aug. 6, 1957

180,741

PEDAL-ACTUABLE SCOOTER-TYPE VELOCIPEDE

Benjamin H. Magoon, Huntington Park, Calif.
Application August 9, 1956, Serial No. 42,566

Term of patent 14 years

(Cl. D34—15)

Fig. 1.

Fig. 2.

Fig. 3.

Fig. 1 is a side view of a pedal-actuable scooter-type velocipede showing my new design;

Fig. 2 is a top view thereof; and

Fig. 3 is a bottom view thereof.

I claim:

The ornamental design for a pedal-actuable scooter-type velocipede, substantially as shown.
